[57] CLAIM

The ornamental design of a crib endboard, as shown and described.

DESCRIPTION

FIG. 1 is a front perspective view of a crib endboard showing our new design;

FIG. 2 is a top plan view thereof;

FIG. 3 is a front elevation view thereof;

FIG. 4 is a side elevation view thereof, the opposite side being a mirror image thereof;

FIG. 5 is a rear elevation view thereof;

FIG. 6 is a bottom plan view thereof; and,

FIG. 7 is an enlarged sectional view taken through line 7—7 of FIG. 3.
